PACKAGING BOX FOR AN ELECTRIC SHAVER
OR SIMILAR ARTICLE

Jerold R. Peterson, Roselle, Ill., assignor to Sunbeam
Corporation, Chicago, Ill., a corporation of Illinois

Filed July 9, 1963, Ser. No. 75,717

Term of patent 14 years

(Cl. D58—11)

FIG. 1 is a front perspective view of a packaging box for an electric shaver or similar article embodying my new design.

FIG. 2 is a rear elevational view thereof;

FIG. 3 is a side elevational view thereof;

FIG. 4 is a top plan view thereof; and

FIG. 5 is an enlarged fragmentary sectional view taken along line 5—5 of FIG. 4.

I claim:

The ornamental design for a packaging box for an electric shaver or similar article, substantially as shown.
